UNITED STATES PATENT OFFICE

JOHN MENGEI, OF OCONOMOWOC, WISCONSIN

CAN COVER AND TOP FEED GUIDE

Application filed November 9, 1928. Serial No. 318,166.

The present invention relates to guides for feeding can covers and tops into can making machines and has for its principal object to provide a guide adapted to feed the covers and tops in a predetermined manner so that the same will enter the can machine in a proper position and to reject the tops or bottoms which are not properly positioned.

In the manufacture of cans, the tops and bottoms thereof are provided with beveled edges which fit on to the can in a predetermined position and should such sections be fed to the machine with this flanged edge improperly positioned an imperfect fit is made in the top or bottom of the can, as the case may be, necessitating the destroying of the can.

It is accordingly the purpose of the present invention to provide a guide in which the tops and bottoms of the can are fed into the can making machine in a proper position so as to insure the perfect manufacture of the article.

One of the important objects of the invention is to provide a guide of this character embodying adjustable features so as to provide for the feeding of top and bottom sections of the can of various sizes.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a fragmentary perspective view of the guide;

Figure 2 is a fragmentary side elevational view thereof;

Figure 3 is a vertical transverse sectional view illustrating the manner in which the guide cooperates with the beveled edge of the top or bottom of the can for feeding the same in a proper position, and

Figures 4 and 5 are similar views showing the manner in which the top or bottom of the can is ejected from the guides when the flanged edge of the same is improperly positioned with respect to the guide.

Referring now to the drawing in detail, wherein for the purpose of illustration, I have disclosed a preferred embodiment of the invention, I provide a pair of spaced parallel guide members 5 and 6 respectively with their upper edges secured by a board 7 which extends substantially throughout the length of said guide members.

The board 7 is secured to the upper edge of the guide member 5 by means of bolt 8 and the opposite edge of the board is formed with transversely extending slotted openings 9 through which bolts 10 are inserted for securing the board to the upper edge of the guide member 6 and providing for the relative adjustment of said guide members.

The inner face of the guide member 5, adjacent its upper edge is formed with a guide track 11 having a channel 12 formed at its under side and within which the upper edge of the can top or bottom 13 is disposed.

The inner surface of the guide member 5, adjacent its lower edge is provided with a longitudinally extending strip 14 having its outer face provided with a series of longitudinally extending rounded bolt heads 15.

The bolt heads 15 may be formed on the strip in any suitable manner, as for instance by forming the same on studs 16 inserted in openings provided in the strip for that purpose. Provision is made for vertically adjusting the strip 14 by means of bolts 17 inserted in vertically extending slotted openings 18 formed in the guide member 5.

The inner face of the guide member 6 is provided with a lining 19 having its surface above and below a point adjacent the lower edge of the lining inclined inwardly as indicated at 20 and 21 respectively whereby to form a longitudinally extending ridge 22 in the surface of the lining at a position slightly above the lower edge thereof, and as clearly illustrated in Figures 3 to 5 inclusive of the drawing.

The ridge 22 of the lining is disposed in a horizontal plane below the row of heads 15. Provision is also made for vertically adjusting the lining 19 with respect to the guide member 6 by means of bolts 23 carried by the lining and extending outwardly through

slotted openings 24 formed in the guide member. A shelf 25 is secured at the inner face of the guide member 6, at the lower edge thereof and is constructed of an angle strip secured along one side to the guide member 6 by bolts 26 and with its opposite side extending upwardly at an inclined angle in a direction toward the guide member 5.

The outer edge of the shelf 25 protrudes 10 outwardly from the guide member 6, a slight distance beyond the vertical plane of the ridge 22. The edge of the can top or bottom, is beveled as shown at 27 and is arranged with its lower edge adapted to rest upon the outwardly disposed edge of the shelf 25 supported in such position that the head 15 and the ridge 22 will engage the opposite sides of the top or bottom of the can.

The guide is slightly inclined downwardly 20 toward the can machine so that upon the feeding of the tops or bottoms in one end of the guide the same will roll in a direction toward the machine.

It will be apparent that should the beveled 25 edge of the top or bottom of the can be placed in the guide in a manner coinciding with the inclined edge of the shelf 25, that the top or bottom will be suitably held within the guide during its travel toward the can machine.

30 However should the beveled edge of the top or bottom be reversed with respect to the inclined edge of the shelf for positioning thereon in a manner as illustrated in Figures 4 and 5 of the drawings, the beveled edge of the top 35 will ride over the edge of the shelf during its movement toward the can machine and thus drop from the guide.

In this manner the feeding of the tops or bottoms of the can in a proper position into 40 the machine is assured. The shelf 25 may also be adjusted vertically for accommodating tops and bottoms of various sizes, by providing vertical slotted openings in the attached edge of the shelf for receiving the bolts 26.

45 It will be observed that the heads 15 are positioned approximately at the center of the top or bottom of the can so that the lower edge thereof will be free to ride over the edge of the shelf when the top or bottom is not 50 properly inserted into the guide.

It is obvious that my invention is susceptible to various changes and modifications in construction without departing from the spirit of the invention or the scope of the appended claims, and I accordingly claim all such forms of the device to which I am entitled.

Having thus described my invention, what I claim as new is:

60 1. A guide of the class described comprising a pair of spaced parallel guide members, a channeled guide formed on the inner face adjacent the upper edge of one of said guide members and a guide shelf secured at the inner face adjacent the lower edge of the other

of said guide members, said channeled guide and said guide shelf cooperating to engage the upper and lower edges respectively of the work and forming a track upon which the same may be moved longitudinally of the guide, and guide means carried by each of said members for engaging opposite sides of the work intermediate its upper and lower edges and arranged to urge the lower edge of the work off the edge of the shelf when said work is placed in predetermined position in the guide. 70 75

2. A guide of the class described comprising a pair of spaced parallel guide members, means at the upper edge thereof for adjustably securing said members relative to each other, a channeled track formed on the inner surface of one of said guide members, adjacent the upper edge thereof, a shelf secured to the inner face to the other of said guide members, adjacent the lower edge thereof, said track and said shelf being adapted to engage the upper and lower edges respectively of the work and means formed on the opposed faces of said guide members for engaging the opposite sides of the work intermediate its upper and lower edges, and cooperating to urge the lower edge of the work off the edge of the shelf when said work is positioned in a predetermined manner in the guides. 80 90 95

3. A guide of the class described comprising a pair of spaced parallel guide members, means at the upper edge thereof for adjustably securing said members relative to each other, a channeled track formed on the inner surface of one of said guide members, adjacent the upper edge thereof, a shelf secured to the inner face to the other of said guide members, adjacent the lower edge thereof, said track and said shelf being adapted to engage the upper and lower edges respectively of the work and means formed on the opposed faces of said guide members for engaging the opposite sides of the work intermediate its upper and lower edges, the work engaging means carried by one of said guide members being disposed above the horizontal plane of the other thereof. 100 105 110

4. A guide of the class described comprising a pair of spaced parallel guide members, means at the upper edge thereof for adjustably securing said members relative to each other, a channeled track formed on the inner surface of one of said guide members, adjacent the upper edge thereof, a shelf secured to the inner face to the other of said guide members, adjacent the lower edge thereof, said track and said shelf being adapted to engage the upper and lower edges respectively of the work and means formed on the opposed faces of said guide members for engaging the opposite sides of the work intermediate its upper and lower edges, the work engaging means carried by one of said guide members being disposed above the horizontal plane 115 120 125 130

of the other thereof, and means for vertically adjusting the work engaging means carried by each of said guide members.

with their beveled edges reversed to the inclination of said inclined guide means.

In testimony whereof I affix my signature.

JOHN MENGEL. 70

5 A guide of the class described comprising a pair of spaced parallel guide members, a rigid connecting member secured to the upper edges of said guide members and providing for the adjustment of said members relative to each other, a channeled track 10 formed on the opposed face of one of said guide members, a shelf secured to the opposed face of the other of said guide members adjacent the lower edge thereof and with the free edge of said shelf inclined upwardly, 15 said track and said shelf cooperating to engage the upper and lower edges of the work when disposed between said members, the inclined edge of the shelf coinciding with a beveled edge formed on the work for retaining 20 the work thereon, means for vertically adjusting said shelf, and work engaging means mounted for vertical adjustment on the opposed faces of said guide members and engageable with the opposite faces of the work.

25 6. A guide for disk members provided with beveled edges comprising a pair of spaced parallel guide members, means attached at the upper edges thereof for securing the same in adjusted position with respect to each 30 other, a channeled track formed on the opposed face of one of said guide members, adjacent the upper edge thereof and adapted for receiving the upper edge of the disks, a vertically adjustable shelf secured to the opposed 35 face of the other of said guide members adjacent the lower edge thereof with the free edge of said shelf inclined upwardly and adapted for engaging the lower edge of the disks, said inclined edge of the shelf coinciding 40 ing approximately with the beveled edge of the disks and operable for retaining the same upon the shelf when the disks are arranged in a predetermined position and guide means adjustably secured to the opposed faces of 45 each of said guide members and engageable with the opposite sides of the disks at different horizontal planes.

7. A guide for disk members provided with beveled edges comprising a pair of 50 spaced parallel guide members, guide means carried at the opposed faces of said guide members and disposed adjacent the upper and lower edges thereof, said lowermost of said guide means having a free edge inclined upwardly to provide a seat for the lowered beveled edge of said disk members when the same are positioned in a predetermined manner within the guides and guide means secured to the opposed faces of said guide members and 55 engageable with the opposite sides of the disk at different horizontal planes, said guide means being disposed with respect to said inclined guide means for guiding the lower edge of the disk off the free edge thereof 60 when the disks are placed within the guide 65
